(57) **CLAIM**

The ornamental design for a slip resistant sole, as shown and described.

DESCRIPTION

FIG. 1 is a bottom plan view of the slip resistant sole of the instant invention;

FIG. 2 is a top plan view of said slip resistant sole depicted in FIG. 1;

FIG. 3 is a front end view of said slip resistant sole depicted in FIG. 1;

FIG. 4 is a back end view of said slip resistant sole depicted in FIG. 1;

FIG. 5 is a right side view of said slip resistant sole depicted in FIG. 1; and,

FIG. 6 is a left side view of said slip resistant sole depicted in FIG. 1.

The surfaces which are not shown, form no part of the claimed design.
